UNITED STATES PATENT OFFICE.

GEORGE S. BLAKESLEE, OF CHICAGO, ILLINOIS.

DISH-WASHING MACHINE.

1,360,716.

Specification of Letters Patent. Patented Nov. 30, 1920.

Application filed December 9, 1916. Serial No. 136,077.

To all whom it may concern:

Be it known that I, GEORGE S. BLAKESLEE, a citizen of the United States, and a resident of Chicago, in the county of Cook and State of Illinois, have invented certain new and useful Improvements in Dish-Washing Machines, of which the following is a specification, reference being had to the accompanying drawings.

10 My invention relates to dish washing machines and it has for one of its principal objects the provision of a form and arrangement of parts by reason of which the dishes to be washed may be maintained for as long 15 a period as may be desired in the washing chamber, and by reason of which the dishes are run through the machine by gravity without the necessity for a power actuated conveyer. It is another object of my invention 20 to provide doors or gates by which the machine is divided into compartments such as to prevent any splashing of the water therefrom during the washing and rinsing operations, and to provide means which may 25 be easily and quickly operated for opening and closing such doors or gates as may be desired. It is another object of my invention 30 to provide a form of basket or carrier for the dishes so arranged as to coöperate with the doors or gates for spacing the baskets or carriers in proper position along the 35 machine. It is another object of my invention to provide a new and improved form of table or apron removably secured in position forming a part of the track or pathway of the carriers through the machine, such tables or aprons being readily removable to afford access to the operating parts 40 within the tank. It is another object of my invention to improve machines of this type in sundry details hereinafter pointed out. The preferred means by which I have 45 accomplished my several objects are illustrated in the drawings and are hereinafter specifically described. That which I believe to be new and desire to cover by this application is set forth in the claims.

In the drawings:—

Figure 1 is an end view of a machine embodying the preferred form of my improved construction;

Fig. 2 is a longitudinal vertical section through my machine, being taken substantially on line 2—2 of Fig. 1;

Fig. 3 is a transverse vertical section taken substantially on line 3—3 of Fig. 2;

Fig. 4 is a fragmentary view showing the manner of mounting the gates or doors, being partly in section taken on line 4—4 of Fig. 2;

Fig. 5 is an enlarged detail illustrating a portion of the means for supporting the track along the tank, being substantially a section taken on line 5—5 of Fig. 6;

Fig. 6 is an enlarged detail of the same parts, being a section taken substantially on line 6—6 of Fig. 5;

Fig. 7 is an enlarged detail illustrating another portion of the track-supporting means, partly in section, taken on line 7—7 of Fig. 3, the part 42 being omitted;

Fig. 8 is a perspective view of the table or apron removably secured at the right hand end of the machine as shown in Fig. 2;

Fig. 9 is a fragmentary view, partly in section, taken substantially on line 9—9 of Fig. 1;

Fig. 10 is a fragmentary view illustrating the construction of the driving chain by which the motor is connected with the paddle wheels as hereinafter described;

Fig. 11 is a section taken on line 11—11 of Fig. 10;

Fig. 12 is a side view of one of the baskets or carriers by which the dishes are carried through the machine;

Fig. 13 is a top view of the basket of Fig. 12, being partly in section taken on line 13—13 of Fig. 12;

Fig. 14 is a transverse section taken on line 14—14 of Fig. 13; and

Fig. 15 is an end view of the basket of Fig. 13 as seen from the right in said figure.

Referring to the several figures of the drawings, in which corresponding parts are indicated by the same reference characters,—

20 indicates a frame having a tank 21 mounted thereon, said tank being divided by a partition 22 into two compartments 23 and 24, the compartment 23 being adapted 100 to contain wash water, while the compartment 24 is adapted to contain rinsing water.

The tank 21 is provided at one side thereof with two paddle wheels 25—26 fixed upon a longitudinally-extending shaft 27. The shaft 27 is adapted to be rotated in counter-clockwise direction as shown in Figs. 1 and 5 3 by means of a sprocket gear 28 fixedly mounted upon said shaft and connected by means of a sprocket chain 29 with a small sprocket wheel 30 rotatable with a third 10 sprocket gear 31. The sprocket gear 31 in turn is driven by means of a sprocket chain 32 extending about a sprocket wheel 33 which is adapted to be rotated at high speed by a motor 34 of any suitable type.

15 A special form of sprocket chain 32 is employed in the construction shown by reason of which such chain is rendered comparatively quiet even when driven at high speed. Such chain 32 comprises links 35 of leather joined by suitable metal links 36.

20 As is best shown in Fig. 2 an inclined track is provided extending longitudinally through the machine alongside of the rotary paddle wheels 25—26. The end portions of 25 this track are provided by means of removable tables or aprons 37—38 at opposite ends of the tank 21. Each of these tables or aprons is supported in position by means of a down-turned flange 39 adapted to hook 30 over a suitable portion of the end wall of the tank 21, the outer end of the apron being supported by means of diagonally-extending brace-bars 40 which are slotted at their inner ends for detachably engaging suitable 35 brackets 41 fixed upon the outer face of the end wall (see Fig. 1).

The intermediate portion of the track or pathway extending through the compartment 23 of the tank comprises two channel-irons 42 supported by two transversely-extending 40 angle-irons 43. The angle-irons 43 are removably supported at one side of the compartment 23 by means of slotted brackets 44, and are supported at their opposite ends by a longitudinally-extending angle-iron 45. The angle-iron 45 in turn is 45 removably supported at its forward end by a bracket 46 mounted upon the partition 22 and removably supported at its rear end by 50 a similar bracket 47 mounted upon the wall of the tank 21. In similar manner the section of the track extending through the compartment 24 comprises two channel-irons 48 supported at their forward ends by means 55 of transversely-extending angle-irons 49 which rest upon longitudinally-extending angle-irons 50 supported at their forward ends by brackets 51 mounted upon the wall of the tank. The rear ends of the channel-irons 48 rest upon transversely-extending 60 angle-irons 52 which are supported by the rear ends of the angle-irons 50, such rear ends of the angle-irons 50 being removably supported by brackets 53 carried by the partition 22.

For preventing splashing of the water from the compartments 23—24 of the tank and also to temporarily stop the baskets or carriers hereinafter described, doors 54, 55 and 56 are provided for closing the ports 70 through which the dishes are adapted to be carried along the longitudinally-extending track. Such doors are slidably mounted in position to close the ports by means of strips 57—58 and brackets 59—60 at opposite sides 75 of each door. The doors are supported in their normal closed position by means of brackets 61 mounted in position to receive the lower ends of the doors. These doors are adapted to be operated by means of 80 cables 62 attached to said doors and extending upward therefrom to sheaves or pulleys 63 to which such cables are attached. The sheaves 63 are fixedly mounted upon a shaft 64 which is adapted to be rotated by means 85 of a cable 65 wound about a sheave or pulley 66 also fixedly mounted on said shaft 64, the lower end of the cable 65 being connected to a foot-lever 67 pivotally mounted on the frame 20. Idler pulleys 68—69 are provided 90 for properly guiding the cable 65. As will be readily understood, when the lever 67 is given an operative stroke in counter-clockwise direction in Fig. 1, the lower end of the cable 65 will be moved upward, serving to 95 pull downward upon the upper end portion of said cable for rotating the shaft 64 in clockwise direction in said figure, and serving to wind the cables 62 about the pulleys 63 for lifting the doors 54, 55 and 56 in unison. Counterbalancing means is provided 100 serving to support a portion of the weight of the doors so as to render them movable easily upward, such means comprising a weight 70 carried by the lower end of a cable 105 71 wound about a sheave 72 fixedly mounted upon the shaft 64.

The dishes to be washed are carried through the machine along the track therethrough by means of baskets or carriages 110 73 which are provided with supporting wheels 74. The dimensions of the baskets or carriers 73 are such that four of such carriers are adapted to substantially fill the entire length of track. A flange 75 on the outer end of the table or apron 38 is adapted to stop the foremost one of the baskets or carriers 73. With a second basket or carrier in position upon the track section within the compartment 24, when the gate 56 is 115 lowered into closing position such gate engages diagonally-disposed projections 76 upon the forward end of the basket, serving to push the basket slightly up the inclined track into centered position within such compartment. The door 55 serves to space in position the carrier or basket located upon the track section within the compartment 23 by engagement with the diagonal projection 76 provided upon the forward end of such car- 120 125 130

rier. The gate 54 in like manner serves by engagement with the projection 76 upon the fourth basket to position such basket in proper position said projections also serve 5 to space the baskets apart when the gates are out of operative position. The baskets are adapted to be carried about by means of transversely-extending bars or handles 77 mounted in the upper ends of the projections 76. Each of the baskets or carriers 73 is provided with longitudinally-extending partitions 78 of any suitable type which are adapted to support in position the dishes placed in the basket.

15 With the motor 34 in operation driving the paddle wheels 25—26 in counterclockwise direction in Fig. 3 so as to pick up water from the tank and to throw it toward the left in said figure upon and across the track 20 extending through the tank, a carrier 73 provided with a load of dishes to be washed is placed in position upon the apron 37. A downward stroke of the foot-lever 67 serves to raise the doors 54—55—56, permitting the 25 carrier 73 to enter the washing compartment 23, this result being attained by gravity. The basket 73 is then stopped in position in the compartment 23, and is maintained in position there until the streams of water 30 dashed upon and across the basket have had an opportunity to thoroughly clean the dishes. The foot lever 67 is then given another operative stroke, serving to raise the doors and to permit the basket to enter the 35 rinsing compartment 24, and at the same time permitting a fresh loaded basket to enter the washing compartment 23 from the apron 37. By the time the dishes in the carrier in the compartment 23 are thoroughly cleaned, the 40 dishes in the carrier in the compartment 24 will have been thoroughly rinsed. The foot-lever 67 is then given another operative stroke permitting the leading basket to run by gravity out of the compartment 24 into 45 position upon the apron 38, and permitting a corresponding change in position of the following baskets. After three baskets or carriers have been placed in position, the baskets will be automatically brought to 50 proper position by the descending doors 54, 55, 56, as above described, coming in contact with the guides 76. As will be readily understood, by a proper manipulation of the doors 54, 55 and 56 a traveling carrier may 55 be stopped in operative position in the several sections of the tank independently of any other carrier or carriers upon the track, such carrier being stopped by the movement of the door into position across the path of the 60 carrier.

65 While the machine herein shown and described is designed primarily for use in washing dishes, the construction described may also be embodied in machines intended for washing a variety of other articles. It

will be understood that I do not wish to restrict myself to the use of a stationary track such as is shown in the drawings adapted for use with wheeled carriers, except as herein-after specifically claimed, but that the invention goes broadly to any suitable supporting means disposed diagonally downward through the tank or receptacle along which supporting means a suitable carrier is adapted to move by gravity, as above described. It is also to be understood that in referring to sliding doors I do not restrict myself to the form of door shown in the drawings, but rather have reference to any suitable type of edgewise-movable door adapted to perform the function described.

What I claim as my invention and desire to secure by Letters Patent, is—

1. In a washing machine, the combination with a suitable casing containing washing and rinsing compartments, inclined means extending through said compartments for supporting a traveling carrier, and means for throwing water upon the contents of said carrier when it is in said compartments, of a 85 wheeled carrier adapted to move through said compartments by gravity, and means between said washing and rinsing compartments for properly positioning said carrier in the washing compartment. 90

2. In a washing machine, the combination of a tank comprising two compartments adjacent to each other, a track extending in inclined position along said tank adapted to permit a carrier to travel by gravity along the track from one compartment to the other, means for throwing water upon the contents of the carrier in each of said compartments, and a sliding door movable into and out of position to shut off one tank compartment 100 from the other and to engage and position a carrier in one of the compartments. 105

3. In a washing machine, the combination of a tank comprising two adjacent compartments, an inclined track along said tank adapted to provide for a wheeled carrier passing by gravity from one compartment to the other sliding doors adapted when in normal position to close off each compartment from the other and from the outside, 110 means for operating said doors in unison, and means for throwing water in each compartment upon a carrier in position upon the track therein. 115

4. In a washing machine, the combination of a tank, a track extending into and through said tank, being inclined downward toward the tank whereby a traveling carrier upon the outer end of said track is adapted to be moved by gravity into position in the 120 tank, means for throwing water upon the portion of the track in said tank, and movable means at the opposite ends of the tank for temporarily stopping said carrier. 125

5. In a washing machine, the combination 130

- of a tank, a track extending along said tank and diagonally downward from one end thereof for supporting a traveling carrier containing the articles to be washed, means 5 in said tank for throwing water upon the contents of said carrier, means for temporarily closing said tank at the ends of said track section for preventing the water from splashing out of said tank and stopping said carrier in operative position thereover, and means for stopping the carrier in position upon the lower end portion of the track when the rear end of said carrier has emerged 10 from said tank.
- 15 6. In a washing machine, the combination of a casing comprising two adjacent compartments, an inclined track extending through said compartments and beyond the opposite ends thereof, a carrier movable 20 along the track, means in each of said compartments for throwing water on a carrier in position upon the track therein, and devices for positioning the carrier in each of said compartments and operating to separate 25 said compartments from each other and to close the end openings into said compartments.
- 30 7. In a washing machine, the combination of a compartment of a length corresponding to that of a traveling carrier for containing articles to be washed, an inclined track extending downward from one end into said compartment, means for throwing water in 35 said compartment upon and across the track therein, sliding doors at each end of the portion of the track in said compartment adapted to close off said compartment for preventing the water from splashing out of the compartment, and means for operating 40 said sliding doors in unison.
- 45 8. In a washing machine, the combination of a compartment, an inclined track extending through said compartment and diagonally downward from one end thereof, means for stopping a traveling carrier in position upon said track just as the rear end of the carrier emerges from the compartment in its movement by gravity along said track, means within said compartment for throwing 50 water upon and across the track therein, and a sliding door adapted to engage the forward end of a second traveling carrier in rear of said first-named carrier and to space said second-named traveling carrier 55 in position on said track.
- 60 9. In a washing machine, the combination of a compartment, an inclined track extending through said compartment and extending outward therefrom at both ends, means for stopping a traveling carrier just as its rear end emerges from said compartment as said carrier moves by gravity along said track, a sliding door adapted to engage the forward end of a second traveling carrier 65 in position on said track in rear of said

first-named carrier for spacing said second carrier in position in said compartment, a second sliding door adapted to engage the forward end of a third traveling carrier in position upon said track in rear of said second carrier for spacing said third carrier away from said second carrier, and means for throwing water upon and across the track within said compartment, said sliding doors being adapted to prevent the 70 water from splashing from said compartment. 75

10. In a washing machine, the combination of two compartments adjacent to each other, an inclined track extending through 80 said compartments and extending at both ends therefrom, means for stopping a traveling carrier on the lowermost portion of said track just as the rear end of the carrier emerges from the adjacent compartment, 85 sliding doors adapted to space in position along said track traveling carriers in rear of said first-named carrier, means for operating said sliding doors in unison, and means in each compartment for throwing 90 water upon and across the track therein.

11. In a washing machine, the combination of a tank comprising a plurality of compartments, sliding doors adapted to close said compartments from each other 95 and from the outside, a track extending through said tank adapted to receive wheeled carriers thereon, means for throwing water upon and across the track in said compartments, means connecting said sliding doors 100 for operation in unison, and means for counter-balancing a portion of the weight of said doors for rendering them more easily operable.

12. In a washing machine, the combination of a tank comprising a plurality of compartments, sliding doors adapted to close said compartments from each other and from the outside, a track extending through said tank adapted to receive movable carriers thereon, means for throwing water upon and across the track in said compartments, a shaft above said doors, cables connecting said shaft with said doors respectively, and means for rotating said shaft 115 for lifting said doors in unison.

13. In a washing machine, the combination of a tank comprising a plurality of compartments, sliding doors adapted to close said compartments from each other 120 and from the outside, a track extending through said tank adapted to receive movable carriers thereon, means for throwing water upon and across the track in said compartments, means connecting said doors 125 for operation in unison, and a lever by a stroke of which said doors may be operated.

14. In a washing machine, the combination of a tank comprising a plurality of compartments, sliding doors adapted to 130

close said compartments from each other and from the outside, a track extending through said tank adapted to receive wheeled carriers thereon, means for throwing water upon and across the track in said compartments, a shaft above said doors, cables connecting said shaft with said doors respectively, another cable connected with said shaft and reversely wound thereon, and a lever connected with said last-named cable for operating said doors in unison.

15. A washing machine, comprising inclined means for supporting a traveling carrier while permitting it to travel thereover by gravity, means associated with said supporting means for throwing water upon the contents of said carrier when it is in a certain position, means for engaging and temporarily positioning said carrier in operative relation to the water throwing means, and means from the path of the carrier for removing said positioning means to permit the carrier to advance.

16. A washing machine, comprising inclined means for supporting a traveling carrier while permitting it to travel thereover by gravity, means associated with said supporting means for throwing water upon the contents of said carrier when it is in a certain position, means movable across the path of said carrier for positioning it in operative relation to the water throwing means, and means for actuating said positioning means to permit the carrier to advance.

35 17. In a washing machine, the combination of a tank, an inclined track extending through said tank and at opposite ends thereof, adapted to permit a movable carrier to move by gravity through the tank, means for throwing water upon and across the track within the tank, said track being formed in sections removably secured in position in alignment with each other, and a sliding partition for separating said track sections from each other.

18. A washing machine comprising a suitable receptacle, an inclined support extending therethrough, a movable carrier adapted to move by gravity along said support, means for throwing water upon said carrier in said receptacle, a projection at one end of said carrier, and means movable across the path of said carrier adapted to engage said projection for positioning the carrier.

55 19. A washing machine comprising a suitable receptacle, supporting means disposed in inclined position through said receptacle and adapted to support a movable carrier while it moves by gravity through said receptacle, means for throwing water upon the articles in said carrier while it is in said receptacle, doors movable across the path of said carrier, in front of and behind the same, respectively, and means for simul-

taneously moving said doors into and out of operative position.

20. A washing machine comprising a suitable receptacle, supporting means disposed in inclined position through said receptacle and adapted to support a movable carrier while it moves by gravity through said receptacle, means for throwing water upon the articles in said carrier while it is in said receptacle, positioning means movable into and out of position to engage said carrier and hold it in washing position, and a lever operatively connected with said positioning means for actuating the same to move it out of engaging relation to the carrier to permit the latter to advance.

21. A washing machine comprising a suitable receptacle, a support extending therethrough, a carrier adapted to move along said support, means for throwing water upon the contents of the carrier, a projection at one end of said carrier, and means movable into engagement with said projection to position the carrier.

22. A washing machine, comprising a suitable receptacle provided with washing and rinsing compartments, an inclined support extending through said compartments and adapted to support a carrier moving by gravity thereon, means in each compartment for throwing water upon the carrier while in such compartment, a door movable across the path of said carrier for engaging and positioning the same in one compartment, and means for moving said door into and out of operative position.

23. A washing machine comprising a suitable receptacle, an inclined support extending therethrough, a movable carrier adapted to move by gravity along said support, means for throwing water upon said carrier in said receptacle, a projection at one end of said carrier, and a door movable across the path of said carrier adapted to engage said projection for positioning the carrier.

24. In a washing machine, the combination with a suitable casing, supporting means extending therethrough, and means for throwing water upon the articles to be washed, of a receptacle adapted to contain the articles to be washed, said receptacle being adapted to travel upon said support, and means projecting at one end from said receptacle for spacing the same apart from an adjoining receptacle.

120 25. In a washing machine, the combination with a suitable casing, supporting means extending therethrough, and means for throwing water upon the articles to be washed, of a receptacle adapted to contain the articles to be washed, said receptacle being adapted to travel through the casing upon said support, means projecting at one end from said receptacle for spacing the same apart from an adjoining receptacle,

and movable means adapted to engage said spacing means to hold said receptacle in operative position.

26. In a washing machine, the combination with a suitable casing, supporting means extending therethrough, and means for throwing water upon the articles to be washed, of a receptacle adapted to contain the articles to be washed, said receptacle be-

ing adapted to travel through the casing 10 upon said support, means projecting at one end from said receptacle for spacing the same apart from an adjoining receptacle, and a movable gate adapted to engage said spacing means to hold said receptacle in 15 operative position and separate adjoining receptacles from each other.

GEORGE S. BLAKESLEE.
